UNITED STATES PATENT OFFICE.

CARL KENTER, OF MAHLSDORF, NEAR BERLIN, GERMANY, ASSIGNOR TO I. SCHWABE,
OF ATLANTIC CITY, NEW JERSEY.

VISE.

1,402,619.

Specification of Letters Patent.

Patented Jan. 3, 1922.

Application filed June 1, 1920. Serial No. 385,740.

To all whom it may concern:

Be it known that I, CARL KENTER, a citizen of the State of Germany, of 113 Hohnowerstrasse, at Mahlsdorf, near Berlin, in the 5 State of Prussia, Germany, have invented certain new and useful Improvements in Vises, (for which I have filed an application in Germany February 18, 1919,) of which the following is a specification.

10 My invention relates to bench vises, and more particularly to that type wherein the same is adapted to be adjusted bodily on a vertical axis, and also to have its clamping jaws jointly adjusted rotatably on a horizontal axis, means being provided for clamping the parts in any adjusted position, and has for its object to provide certain improvements in the construction of the same as hereinafter more definitely will be pointed out 15 and claimed, reference being had to the accompanying drawings, in which:—

20 Figure 1 is a longitudinal sectional view of my improved bench vise.

Figure 2 is a transverse sectional view, 25 taken on the line II—II of Figure 1.

Figure 3 is a similar view taken on the line III—III of Figure 1.

Figure 4 is a view similar to Figure 1, showing a modified construction.

30 Figure 5 is a transverse sectional view taken on the line V—V of Figure 4.

Similar numerals of reference denote corresponding parts in the several views.

In the said drawings, referring more particularly to Figures 1, 2 and 3, the reference numeral 1 denotes the base of the vise, the same being adapted to be screwed or otherwise permanently fixed to a bench or other support, and being formed in its upper surface with an annular recess 2, which at its lower portion is enlarged at 3, as shown. Seated upon said base is the body 4 of the vise, the same being formed on its underside to fit into the recess 2, as shown, and being provided with a pair of bolts 5 having their headed lower ends fitting in the enlarged portion 3 of the recess 2, and being provided with suitable nuts 6, whereby the body 4 may be clamped firmly to the base 1 when adjusted. The body 4 is formed hollow, and its side walls are apertured longitudinally to receive at one side the rear projecting circular portion 7 of the inner jaw 8 of the vise. This portion 7 is recessed annularly at 9 to receive a segmental split-ring 10 loosely dis-

posed therein. The base 4 on one side is provided with a screw-threaded aperture to receive a screw bolt 11 passing therethrough and adapted to engage a recess formed in the split-ring 10, as shown in Figure 3. Through the opposite side of the base 4 there is provided a headed screw-bolt 12, adapted to be screwed against the split-ring 10 to clamp the same against the circular portion 7 of the inner jaw 8, in a manner readily understood. Passing through a central aperture in the inner jaw 8 and the circular portion 7 thereof, is a sleeve 13, the same extending completely through the body 4 and contacting at its rear end against a plate 14, screwed to said body as shown. Said sleeve 13 is shouldered at 15 to provide a rear stop for the circular portion 7 of the jaw 8, and is formed interiorly at approximately its longitudinal center with a screw-threaded portion adapted to engage the screw-threaded portion 16 of the operating bolt 17, said bolt extending forwardly and having an additional bearing at 18 in the sleeve 13, as shown. The outer jaw 19 of the vise is formed with 80 an inwardly projecting portion 20 adapted to fit over the sleeve 13, the same being slotted longitudinally for a portion of its length, and formed with projections 21 through which is passed a screw-bolt 22, whereby said 85 split portion may be adjusted on the sleeve 13 to effect a snug fit thereon. The circular portion 7 of the rear jaw 8, and the portion 20 of the forward jaw 19 are recessed to receive a locking strip 23, the same engaging a 90 similar longitudinal recess in the sleeve 13, whereby the jaws 8 and 19 are retained against any but a common rotary movement on said sleeve. The outer jaw 19 is retained in position on the sleeve 13 by means of a 95 nut 24 and a screw-bolt 25, said screw-bolt also retaining in position a recessed plate 26, which fits over and engages in a groove 27 formed in the front end of the bolt 17, whereby longitudinal movement imparted to said 100 bolt will be transmitted to said jaw 19.

To assemble the structure, the sleeve 13 with the inner jaw 8 positioned thereon, is seated in the body 4 to position and the bolt 11 screwed to engage the depression in the 105 split-ring 10, thereby locking the parts against longitudinal displacement. The outer jaw 19 is now slid into position and the nut 24 and recessed plate 26 fixed in position by means of the screw 25, it being understood 110

that the bolt 17 has been previously disposed in the sleeve 13. By adjusting the screw 22, the desired fit between the sleeves 20 and 13 may be obtained as will be understood.

5 When so assembled and ready for operation, the vise as a whole may be adjusted on its vertical axis upon the base 1 by loosening the nuts 6, and may then be clamped in any adjusted position. The jaws 8 and 19 may 10 be adjusted on their horizontal axis by loosening the bolt 12, which will release the split-ring 10 from its clamping action and permit rotation of said jaws on the sleeve 13. The engagement of the recessed plate 24 with the 15 groove 27 in the bolt 17, will cause the outer jaw 19 of the vise to be moved longitudinally in unison with any movement of said bolt 17 due to its screw-threaded engagement with the sleeve 13, said longitudinal movement 20 being effected in the usual manner by the rotation of said bolt 17 by means of the handle 28.

In Figures 4 and 5, I have shown a slightly modified construction, wherein two pairs of 25 jaws 8' and 19' are shown, one pair having conventional flap-engaging faces 29, and the other pair having recessed-engaging faces 30 in order better to clamp round work to be operated on. In this construction, the screw- 30 threaded portion 16' of the operating bolt 17' is differently disposed, but the operation is the same. The means for clamping the body 4' to the base 1' is somewhat different, the same comprising a bolt 31 screw-threaded 35 on its opposite ends and passed through the supporting bench 32, and into the bottom of the body 4' as shown. A lock nut 33 is provided thereon, as well as a wing-nut 34 at its lower end. By loosening said wing-nut 40 the body 4' may be rotated upon the base 1', turning with it said bolt 31, and by tightening said wing-nut 34, the body 4' may be clamped tightly to said base 1'.

Having thus fully described the invention, 45 what I claim as new and desire to secure by Letters Patent, is:—

1. A bench vise, comprising a body, a horizontally disposed sleeve rotatably mounted in said body, an inner clamping 50 jaw keyed to said sleeve, an outer clamping jaw splined to said sleeve, means for locking said sleeve and jaws against axial movement in said body but permitting rotary movement, separate means for locking said 55 sleeve and jaws against rotary movement, and means for adjusting one of said jaws toward or from the other jaw.

2. A bench vise, comprising a body, a horizontally disposed sleeve rotatably 60 mounted in said body, an inner clamping jaw splined to said sleeve and formed with a circular portion projecting into said body and abutting a shoulder on said sleeve to prevent longitudinal displacement of the 65 latter, an outer jaw splined to said sleeve,

means for adjusting said outer jaw relatively to said inner jaw, a segmental split-ring disposed in an annular groove in the circular portion of said inner jaw, means for locking said sleeve and jaw against axial 70 movement in said body but permitting rotary movement, separate means for locking said sleeve and jaws against rotary movement, and means for adjusting one of said jaws toward or from the other jaw. 75

3. A bench vise, comprising a body, a horizontally disposed sleeve rotatably mounted in said body, an inner clamping jaw splined to said sleeve and formed with a circular portion projecting into said body 80 and abutting a shoulder on said sleeve to prevent longitudinal displacement of the latter, an outer jaw splined to said sleeve, means for adjusting said outer jaw relatively to said inner jaw, a segmental split-ring disposed in an annular groove in the circular portion of said inner jaw, a screw-bolt in said body adapted to engage a recess 85 in said split-ring to lock said inner jaw and sleeve against axial movement, and a separate screw-bolt in said body adapted to compress said ring against the circular portion of said inner jaw adjustably to clamp said jaw and sleeve against rotation. 90

4. A bench vise, comprising a body, a horizontally disposed sleeve mounted in said body, inner and outer clamping jaws mounted in said sleeve, said outer jaw being formed with a split extension embracing said sleeve, a screw-bolt engaging said split 95 portion for varying the pressure of said portion on said sleeve, and means for adjusting said outer jaw on said sleeve relatively to said inner jaw. 100

5. A bench vise, comprising a body, a horizontally disposed sleeve mounted in said body, an inner clamping jaw fixed on said sleeve, an outer clamping jaw splined to and axially adjustable on said sleeve, a screw shaft engaging threads in said sleeve and adjustable axially therein, and a recessed plate fixed to said outer jaw and engaging an annular groove in said screw shaft whereby axial movement of the latter will be imparted to said outer jaw. 110 115

6. A bench vise, comprising a body, a horizontally disposed sleeve mounted in said body, integral oppositely disposed inner jaws fixed on said sleeve, similar integral oppositely disposed outer jaws splined on said sleeve, means for adjusting said outer jaws axially on said sleeve, and means permitting rotary adjustment of said sleeve and jaws in said body. 120

In testimony whereof I affix my signature 125 in presence of two witnesses.

CARL KENTER.
